UNITED STATES PATENT OFFICE.

JOSEPH D. MORLEY, OF LAKE PLEASANT, NEW YORK.

BOAT-BUILDER'S RIVETING-JACK.

SPECIFICATION forming part of Letters Patent No. 781,542, dated January 31, 1905.

Application filed June 21, 1904. Serial No. 213,565.

To all whom it may concern:

Be it known that I, JOSEPH D. MORLEY, a citizen of the United States, and a resident of Lake Pleasant, Hamilton county, New York, 5 have invented certain Improvements in Boat-Builder's Riveting-Jacks, of which the following is a specification.

My invention consists of a jack for use in making or repairing clinker-built boats—that is to say, boats in which the successive strakes overlap and are riveted together—the object of my invention being to permit of the setting and clenching of the rivets by one man who has both of his hands free for the purpose.

15 This object I attain in the manner herein-after set forth, reference being had to the accompanying drawings, in which—

Figure 1 represents my improved jack in position for use in clenching a rivet. Fig. 2 is 20 a side elevation of the jack. Fig. 3 is an end elevation showing the jack applied to the boat, and Fig. 4 is an enlarged perspective view of one of the elements of the jack.

In building or repairing clinker-built boats 25 two men are ordinarily needed, one to hammer the rivets and the other to hold the weight against which the rivets are clenched or upset, since the work cannot be effectively done by one man manipulating a hammer with one 30 hand and holding the weight with the other.

The object of my invention has been to provide a jack for properly supporting in respect to the strakes of the boat the weight against which the rivets are clenched, so that the man 35 who is driving the rivets will have both hands free.

The jack consists of a suitable vertical frame 1, having guides for a rack-bar 2, which carries at its upper end a pivoted and swinging 40 head 3, with projecting rib or flange 4 on its inner face for engaging with the under edge of that strake of the boat which is to be riveted, and thereby holding the head in proper position to upset or clench the rivets driven 45 through the overlapping strakes from the inside of the boat, the fact that the head is pivoted on the upper end of the rack-bar 2 permitting it to assume any desired angle, and thus accord with the varying angles assumed 50 by the strakes in the different portions of the

boat. The rack-bar 2 is adjusted to different vertical positions by means of a sliding pawl 5, likewise vertically guided on the frame 1 and engaging at its upper end with the teeth of the rack-bar 2, with which it is maintained 55 in contact by means of a spring 6, lifting movement being imparted to the pawl by means of a treadle 7, hung to the lower portion of the frame 1.

In order to render it unnecessary to constantly press with the foot upon the treadle 7 during the time that the jack is in use and in order to prevent the pawl and rack-bar from falling, I provide a cam-lever 8, pivoted to the upper portion of the frame 1 and bearing 60 against the back of the pawl 5, so that when the rack-bar has been lifted to the desired height the pawl can be acted upon by this cam-lever, so as to jam it against the rack-bar, and thereby jam the latter in its guides with sufficient force to prevent it from falling. In order to maintain the head 3 in close contact with the strake which is being riveted into place, suitable means may be employed for anchoring the frame 1; but I prefer to provide 65 the rack-bar 2 with a projecting arm 9, against which the knee or other part of the person of the workman can be pressed with the effect of likewise pressing the head 3 toward and in contact with the strake of the boat. 80

It will be evident that the device described provides means whereby the head 3 can be pressed with sufficient force against the outer face of any desired strake of the boat, thus leaving both hands of the workman free to insert and drive the rivets whereby the successive strakes are secured together. 85

Having thus described my invention, I claim and desire to secure by Letters Patent—

1. A boat-builder's riveting-jack consisting 90 of a supporting-frame, a vertically-movable member mounted thereon and provided with a head having a side bearing-face against which the rivets can be clenched, substantially as specified. 95

2. A boat-builder's riveting-jack consisting 100 of a supporting-frame, a vertically-movable member mounted thereon and provided with a head having a side bearing-face against which the rivets can be clenched, and a rib or shoul-

der substantially at a right angle to said clinching-face, substantially as specified.

3. A boat-builder's riveting-jack consisting of a supporting-frame, a vertically-movable member mounted thereon, a head pivoted thereto, and presenting a side bearing-face against which the rivets can be clenched, substantially as specified.

4. A boat-builder's riveting-jack consisting of a frame, having a vertically-movable rack-bar thereon, with head for bearing against the strake to be riveted, a pawl for actuating said jack, and a cam-lever for engaging said pawl, and locking the same and the rack-bar in adjusted position, substantially as specified.

5. A boat-builder's riveting-jack consisting of a frame, a vertically-adjustable bar supported thereby and having a head for bearing against the strake to be riveted, and an arm extending laterally with respect to said bar through the medium of which pressure can be exerted laterally upon said head to press it against the strake, substantially as specified.

In testimony whereof I have signed my name to this specification in the presence of two subscribing witnesses.

JOSEPH D. MORLEY.
